I claim the ornamental design of a toy water gun, as shown and described.

DESCRIPTION

FIG. 1 is a right side perspective view of a toy water gun showing my new design;

FIG. 2 is a right side elevation view of the toy water gun;

FIG. 3 is a top plan view of the invention.

FIG. 4 is a front elevation view of the invention.

FIG. 5 is a rear elevation view of the invention.

FIG. 6 is a left side elevation view of the invention; and,

FIG. 7 is a bottom plan view of the invention.

The broken lines shown in FIG. 1 are for illustrative purposes only and form no part of the claimed design.
